CLAIM

We claim the ornamental design for a sensor enclosure, as shown and described.

DESCRIPTION

FIG. 1 is a front and left side perspective view showing our new design for the sensor enclosure;

FIG. 2 is a front elevational view thereof, which is identical to the rear elevational view;

FIG. 3 is a right elevational view thereof, being an identical to the left elevational view;

FIG. 4 is a bottom view thereof; and,

FIG. 5 is a top view thereof.
